(57) **CLAIM**

The ornamental design for an aquatic animal shaped sheathing, as shown and described.

DESCRIPTION

FIG. 1 is a perspective front view of an aquatic animal shaped sheathing showing my new design;

FIG. 2 is a perspective back view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of the sheathing with an insert in its cavity and affixed with an attachment on top;

FIG. 10 is a perspective view of the sheathing separated with the attachment;

FIG. 11 is a coronal sectional view along axis 11 from FIG. 7; and,

FIG. 12 is a coronal sectional view along axis 12 from FIG. 7.

Broken lines illustrate portions of the aquatic animal shaped sheathing or environmental subject matter that form no part of the claimed design.
